UNITED STATES PATENT OFFICE.

ROBERT E. WILSON, OF CHICAGO, ILLINOIS, ASSIGNOR TO STANDARD OIL COMPANY, OF WHITING, INDIANA, A CORPORATION OF INDIANA.

BREATHER BAG.

Application filed March 26, 1924. Serial No. 702,029.

The present invention relates to improvements in breather bags intended for use in connection with vented storage tanks for volatile liquids, such as gasoline, and will be 5 fully understood from the following description, illustrated by the accompanying drawings, in which:

Figure 1 is a vertical sectional view through a breather bag embodying the present invention;

Fig. 2 is a side elevation thereof;

Fig. 3 is a detail plan view of one end of the breather bag, the protecting housing being shown in section;

15 Fig. 4 is a broken plan view, on an enlarged scale, of one of the riders or weights for the breather bag;

Fig. 5 is an end elevation of the rider or weight shown in Fig. 4; and

20 Fig. 6 is a vertical sectional view through a portion of the side of the bag and a side support therefor;

Fig. 7 is an elevational view of a storage tank and a breather bag and the connections 25 therebetween.

In my prior application Serial No. 636,590, filed May 4, 1923, I have disclosed that loss by evaporation from storage tanks containing volatile liquids, and particularly 30 gasoline, may be substantially prevented by connecting a vent pipe from such tanks with a collapsible bag, preferably of fabric so treated so as to be substantially impervious to the vapors of the stored liquid. In that 35 application I have also disclosed a specific form of construction and support of such an expansion or breather bag.

The present application relates to improvements in the construction and support of the 40 expansion or breather bag, and in means for counterbalancing the extra pressure caused by the weight of vapors in the vent pipe, thereby maintaining substantially atmospheric pressure in the top of the storage 45 tank. As illustrated in the drawings, 8 is a storage tank provided with a vent pipe 12 which leads from the vapor space of the tank 8 to the breather bag 10. The vent pipe 12, is provided with a suitable pressure and vacuum relief valve or seal 9. The breather bag 10 may suitably be of fabric material, for example, as described in my prior application Serial No. 636,590, filed May 4, 1923, and of substantially cylindrical form, the bag being housed in a suitable protective

bag house 11. The vent pipe 12, leading from the single vent of the storage tank 8 containing gasoline or other volatile liquid, is brought into the bag house 11 from the bottom, and passes through a protecting 60 metal plate 13, lying on the floor of the bag house, to the interior of the bag, the size of which is determined by the size of the storage tank or tanks to which it is connected.

65 The bag 10 is supported within the bag house 11 by means of suitable supports at an intermediate elevation at suitable points around the periphery of the bag, for example, at the sides and ends. The support of 70 the bag may be effected, for example, by placing a bar 14 (suitably a length of gas pipe bent to conform with the shape of the bag when distended, if necessary) in a fold 75 15 of the fabric of the bag and clamping the bar and the enfolding bag material between suitable clamping members, for example, the wooden planks 16 provided with grooves 17 in which the bar 14 and enfolding bag material lie. In the form illustrated, the clamping members 16 are held together by means 80 of bolts 18 and those at the sides are supported by means of the supporting members 19 and those at the ends by means of the supporting means 20.

85 The pressure in the vapor system including the expansion bag and vent pipe and extending back to the vent of the tank is controlled by means of suitable riders or weights resting upon the bag and movable upwardly and downwardly with its upper side. As 90 illustrated in the drawings, these riders or weights may suitably be formed to correspond roughly with the shape of the contacting surface of the bag, for example, as boat-like or trough-like members 21, of which one 95 is provided on each side of the longitudinal median line of the bag, the riders 21 being held in spaced relation by bars 22 bent to a conformation which will not interfere with 100 the free expansion of the bag. The weights or riders 21 rise and fall with the upper portion of the bag, and by reason of their disposition on opposite sides of the apical point or center of the bag, when expanded, they 105 retain their relative positions during the movements of the bag. The weights or riders 21 are so constructed or weighted that a relatively slight excess pressure within the bag will be sufficient to maintain a balanced pres- 110

sure in the vapor space of the tank; in practice, for example, for gasoline excess pressure of 0.1 to 0.3 inches of water has been found to be a proper pressure for the purpose, depending upon prevailing temperature conditions.

In order to cause a substantial uniformity of pressure of vapor in the bag at all points in its expansion and collapse, the suspending rope 26 is connected to each of the weights or riders 21. These ropes are, in the embodiment illustrated, joined at 26 to form a single rope 27 which passes over two horizontally spaced pulleys 28 and is connected 15 to one end of a chain 29. To the other end of the chain 29 a partial counterbalancing weight 30 is connected by a rope 31, the weight of which may be varied in accordance with variations in the weight of vapor 20 in the vent pipe, etc.

With the bag expanded, as shown in Fig. 1, the weights or riders 21 exert their least effectiveness. In that position they are counterbalanced by both weight 30 and chain 29. 25 As the bag collapses, the riders 21 exert a higher effective pressure, and the chain 29 passes to a horizontal position between pulleys 28, and no longer acts as a counterbalance for the riders. As the bag collapses 30 farther, the effective pressure exerted by the riders becomes greater, the chain 29 passing to a depending position above the riders, adding its weight to theirs.

It is readily apparent that suitable means 35 may be employed for maintaining a substantially constant effective pressure by means of the weights or riders 21, if desired.

Although the present invention has been described in connection with the details of 40 construction of a specific embodiment thereof, it is not intended that these details shall be regarded as limitations upon the scope of the invention, except as hereinafter set forth in the claims.

45 I claim:

1. A vapor expansion bag for connection to the vent of a storage tank for volatile liquids having lateral supporting means at an intermediate elevation, and spaced weighting means riding upon the bag on opposite sides of its apical point when distended.

50 2. A collapsible bag having lateral sup-

porting means, a storage tank vent pipe connected thereto, and means for applying a variable force to the exterior of said bag 55 thereby maintaining substantially atmospheric pressure in the vapor space of the tank.

3. A collapsible bag having lateral supporting means at an intermediate elevation, 60 a storage tank vent pipe connected thereto, and a weight member resting upon and supported by the bag.

4. A collapsible bag, a storage tank vent pipe connected thereto, lateral supporting 65 means for the bag, at an intermediate elevation, weight members resting upon said bag, and spacing means for holding said weight members in spaced relation on opposite sides of the median line of the bag. 70

5. A collapsible bag having lateral supporting means at an intermediate elevation, weighting means resting upon the upper surface of the bag, and means for varying the effective weight of the weighting means 75 as the bag collapses to maintain substantially constant pressure on the contents of the bag.

6. A collapsible bag having lateral supporting means at an intermediate elevation, 80 weighting means resting upon the upper surface of the bag, counterbalancing means for said weighting means, and connecting means between the weighting means and the counterbalancing means, said connecting 85 means having a substantial weight whereby the effective weight of the weighting means is increased as the bag collapses.

7. An expansion bag and means for supporting the sides of said bag at an intermediate elevation thereof, said supporting means including a bar within a fold of the material of the bag and clamping means exterior to the bag and engaging the bar within the fold of the material. 90

8. An expansion bag and means for supporting the sides of said bag at an intermediate elevation thereof, said supporting means including a bar within a fold of the material of the bag in the interior thereof, 100 and clamping means exterior to the bag and engaging the bar within the fold of the material.

ROBERT E. WILSON.
